PNEUMATIC CONTROL INSTRUMENT

Paul F. Shivers, Wabash, Ind., assignor to Minneapolis-Honeywell Regulator Company, Minneapolis, Minn., a corporation of Delaware

Application December 31, 1937, Serial No. 182,787

10 Claims. (Cl. 236—47)

The present invention relates to pneumatic control apparatus and is more particularly concerned with an improved compressed air thermostat and pneumatic relay device for providing more effective and efficient control of the temperature in the rooms of a building during the daytime and at night.

In school houses or other buildings, it is a matter of fuel economy to maintain lower temperatures at night when the building may be unoccupied. In the present invention, thermostats may be employed to control steam valves in various rooms of a building and may be reset to maintain lower temperatures at night by changing the operating pressure in the pneumatic system at a remote point. Pneumatic relay devices are often employed with air operated control instruments for multiplying the capacity of the instrument whereby larger valves or other devices may be controlled. My invention employs a relay of improved construction such that while the operating pressure in the pneumatic system may be changed for resetting the thermostats, the pressure which can be transmitted by the relay to valves, damper motors, or the like, cannot exceed a predetermined value. Such automatic valves or damper motors are usually designed for complete closure at a predetermined pressure, and my invention is designed to prevent a higher pressure from being impressed upon them with consequent danger of harmful and damaging results.

Frequently in school buildings, or the like, the janitor may reset the thermostats in all the rooms of the building from a remote point, for example from the basement, at a certain time in the evening. Often it may be desired to maintain certain rooms at the daytime temperature after that time to accommodate people using the rooms later than usual. My improved thermostat is so constructed that it may be reset to a night setting from a remote point and also can be manually returned to the day setting and back to the night setting as desired so that individual rooms may be kept warm as long as necessary without supplying heat to the entire building. The instrument is also so arranged that it can be accurately adjusted in either the day or night position to maintain a desired temperature.

In my invention the normal daytime pressure employed in the pneumatic control system is 15 lbs. while at night this pressure is increased to 30 lbs. for accomplishing the resetting operation of the control instruments. These pres-

sures may, of course, be varied within the contemplation and scope of the invention.

It is an object of my invention to provide a pneumatic relay device so constructed that the pressure permitted to be impressed on devices being controlled cannot be higher than a predetermined value even though the supply pressure in the pneumatic system be increased above this value.

A further object of my invention is to provide a pneumatic control system having control instruments operating pneumatic relays and capable of being simultaneously reset by changing the supply pressure in the pneumatic system, the pneumatic relays being so constructed that the pressure therein does not exceed the normal supply pressure even if the supply pressure is increased.

Another object of my invention is to provide a novel pneumatic temperature responsive control instrument, the control point of which can be reset from a remote point by changing the supply pressure in the pneumatic system and which has a device incorporated therein for returning the control point to the daytime setting at will after it has been reset to a night-time setting.

It is a further object of the invention to provide improved pneumatic control apparatus for heating systems and the like whereby more flexible control may be exercised over the system and more efficient and economical operation will result.

Further objects and advantages of the invention will make themselves apparent to those skilled in the art from the following detailed description of the invention and accompanying drawings thereof.

Figure 1 is a perspective view of my complete assembled control instrument exclusive of its casing.

Figure 2 is a side view of the instrument of Figure 1, having certain portions shown in cross-section, illustrating the arrangement of the parts when the instrument is on the normal daytime setting.

Figure 3 is a side view similar to Figure 2 but illustrating the position of the parts when the instrument is on the night setting.

Figure 4 is a side view of a detail portion of the instrument as seen on Figures 2 and 3 but illustrating the position of the parts shown when the instrument has been manually returned to the daytime setting after having been reset to the night setting.

Figure 5 is a side elevation in cross-section of the improved pneumatic relay forming part of my control instrument taken along the line 5-5 of Figure 1.

Figure 6 is a more or less diagrammatic illustration of a complete pneumatic control system having some of the elements thereof in section and showing the manner of interconnecting the parts of my control instrument with the system, and the operative relationship therebetween.

Figure 7 is a side elevation partly in cross-section of a slightly modified form of the pneumatic relay of Figure 5.

Referring to Figures 1, 2 and 3 of the drawings which represent my control instrument in assembled form, numeral 1 indicates the body or frame of the instrument. The body 1 has a pair of oppositely arranged lugs, one of which is visible at 2, which are arranged for attachment of the body to a pipe head 3 by means of screws 4. The pipe head 3 is a cast metal plate having connections for a pair of pipes 5c and 6, one of which provides for communicating a constant pressure to channel 5a and to the instrument and the other of which provides for conveying a pressure regulated by the instrument from channel 6a to a device such as a valve or damper motor to be controlled. Interposed between the body 1 of the instrument and the pipe head 3 is a gasket 9 for providing a leak-proof joint between the body 1 and the pipe head 3.

The body 1 has a pair of arms 10 and 11 extending therefrom which are perforated at their ends to receive a shaft 12. Pivoted on the shaft 12 are a bell-crank lever 15 and a lever 16. The lever 16 has a pair of lugs or ears 17 through which the shaft 12 extends. Connected to the lower part of lever 16 by riveting or by other suitable means is one leg of a U-shaped member 20. The opposite leg of the U-shaped member 20 is shorter and has attached thereto by riveting, or the like, a thermostatic or bimetallic element 21. The bell-crank lever 15 has a pair of integral ears or lugs similar to the lugs 17 of lever 16 and through which also extends the shaft 12. The downwardly extending part of the bell-crank lever 15 is forked, forming a pair of arms 22 which are integrally formed with the lugs engaging the shaft 12. The arms 22 engage with the surface of a diaphragm 23 on the movable end of a bellows 24 which is mounted on the body 1 of the instrument. The diaphragm 23 also carries a member 25 which engages the lever arm 16 as shown. The bell-crank lever 15 also has a portion 27 which extends generally at right angles to the arms 22. A branch channel 5b communicates pressure from pipe 5c to bellows 24.

The body 1 of the instrument is broader at its central portion and has extending members 30 which are tapped to receive the screws 31. The screws 31 extend through the opposite ends of a yoke 32 which is spaced from the body 1 of the instrument by coil springs 33. Numeral 35 indicates a member in screw threaded relation with the central portion of the yoke 32 and rotatable by means of a knurled knob, or the like, 36. The end of the screw member 35 serves as a stop for the lever 16 when the said lever is moved to the right as seen on the figures and which is adjustable by turning the knurled knob 36 to the right or left. The assembly formed by the lever member 16 and the U-shaped member 20 is resiliently engaged between the member 25 at the end of the bellows 24 and between a forked resilient metal spring 40. The forked spring 40

engages with the inner side of the longer leg of the U-shaped member 20 as shown, and each of its prongs or forks is perforated at the end and engaged on one of the screws 31 between coil springs 33 and the body 1 of the instrument. It will readily be seen that spring 40 tends to bias the lever 16 in a clockwise direction around its pivot and against the force exerted by the bellows 24.

Extending through holes formed in the inner portions of the arms 10 and 11 of the body 1 is a shaft 42. Encircling the end of the shaft 42 which extends beyond the arm 10 is a coiled torsion spring 45, one end of which is attached to the arm 10 and the other end of which is attached to the shaft 42. A portion of the shaft 42 between the arms 10 and 11 has a flattened surface, as can be seen on Figures 2 and 3. On the opposite end of the shaft 42 is an operating lever or arm 46 having a knurled portion 47 and a pair of prongs or fingers 48 and 49 diametrically opposite the knurled portion 47. The shaft 42 can be moved against the force of the torsion spring 45 by the operating lever 46 and is limited in its angular movement in either direction by engagement of the fingers 48 and 49 with a stop member 50. Whenever the shaft 42 is rotated so that the flattened surface, as seen on Figures 2 and 3, is moved to any position except horizontal, the torsion spring tends to return the shaft to its original position. It will be seen from the cross-section of the shaft 42 that one edge of the flattened surface which is at the central portion of the shaft is slightly chamfered or bevelled forming a very small flat surface indicated at 53. When the bellows is in its normal position having a normal pressure of 15 lbs. therein, as shown in Figure 2, the arm 27 of bell-crank lever 15 need not engage the shaft 42. However, when the bellows 24 is in its extended position, that is when there is a pressure of such as 30 lbs. per sq. inch therein as employed in this invention, as shown in Figure 3, the arm 27 of the bell-crank lever 15 engages the flat surface of the shaft 42. It will be seen in Figure 3 that extension of the bellows 24 has moved the arms 22 of bell-crank lever 15 to the right, thereby bringing arm 27 into engagement with shaft 42, and also the lever arm 16 and the bimetallic element 21 have been moved in a counter-clockwise direction about the pivot point of lever arm 16. This described movement of the parts has been brought about by the force exerted by the pressure within bellows 24 against the opposite force exerted by the bellows walls and spring 40. It will be seen in Figure 3 that the upper portion of the lever 16 is engaged with the screw member 35 which forms a stop therefor. The assembly formed by the lever 16, U-shaped member 20 and bimetallic element 21 may now be returned to its original position by rotation of the shaft 42 in a counter-clockwise direction. Rotation of shaft 42 in a counter-clockwise direction will force arm 27 upwardly which will force arms 22 to the left, thereby compressing bellows 24 to its original position, which permits spring 40 to return the assembly including bimetallic element 21 to its original position. When shaft 42 has been rotated counter-clockwise a predetermined degree, the small flat surface 53 will engage with the arm 27, as clearly indicated on Figure 4. This rotation of shaft 42 will be against the force exerted by torsion spring 45 but the force of bellows 24 against the small flat portion 53 of shaft 42 will cause the shaft 42 to be retained

in its position by reason of the friction between the said shaft 42 and arm 27. Release of the pressure within bellows 24, that is, a reduction in the above mentioned pressure from 30 lbs. to 15 lbs., would cause the friction between the shaft 42 and the arm 27 to be reduced sufficiently to permit torsion spring 45 to return shaft 42 to its original position with the relatively large flat side horizontal as seen in Figure 2.

The lower portion of the body 1 of the instrument carries a rotatable dial 60 having a knurled edge, as shown. The dial 60 has a cam 61, the cam surface of which is of helical conformation. The lower part of the lever 16 is offset to one side of the U-shaped member 20 and is bent over as at 62 so as to engage with the helical edge of the cam 61 when the assembly formed by lever 16, U-shaped member 20 and bimetallic element 21 is in the position shown in Figure 2. Dial 60 has a circular slot 63 through which extends a pointer member 64 to indicate dial readings on the surface of the dial 60, as shown. The pointer member 64 is attached to a vertical support 65 which is attached by a screw 66 to the body 1 of the instrument. This screw 66 also secures a lug or guide 66a for the dial 60 to the body 1 of the instrument. It will readily be seen that rotation of the dial 60 in either direction will, by reason of the cam 61, cause the lever 16 to be moved a small amount in either direction about its pivot. Obviously, the thermostatic element 21 is moved whenever the lever 16 is moved by rotation of the dial 60. The dial 60 and the cam member 61 provide for adjustment of the instrument when it is in its normal daytime position, as seen in Figure 2. The lower portion of dial 60 and pointer 64 protrude through a slot in the casing of the instrument so that the adjustments of the daytime temperature can conveniently be made without removing the casing. It will be noted that a screw 67 extends between the legs of the U-shaped member 20 near its bottom portion and provides an additional means for adjusting the instrument by turning the screw and thereby drawing the legs of the U together or forcing them apart. Such adjustment of the screw 67 obviously adjusts the relative position of the thermostatic element 21. This adjustment is a factory adjustment and cannot be made without removing the casing which normally encloses the instrument.

The upper portion of the body 1 of the instrument forms a casing 100 of general cylindrical conformation. The casing 100 houses the relay mechanism which, as has been previously explained, forms a part of the instrument and which will be described in detail hereinafter. Numeral 71 indicates a tube having a bleed port therein such as is ordinarily used in connection with pneumatic control instruments and which extends from casing 100. The bleed port and the control thereof may be referred to as a pilot valve for a large valve forming part of the relay device. Also extending from casing 100 is a support 72 suitably secured to the casing by screws 73 to which is pivoted a vane 74. The vane 74 swings freely about its pivot and at its lower end carries a weight 75 on one side and on the other side engages with the upper end of the bimetallic thermostatic element 21. On the side of the vane 74 opposite the weight 75 is a glass baffle plate 76 retained within a suitable casing 77, arranged to engage the conical end of the tube 71 having the bleed port therein. Movement of the thermostatic element 21 tending to rotate the vane 74

in a counter-clockwise direction will tend to move the baffle plate 76 away from the bleed port in tube 71, thereby increasing the rate of bleed, while movement of the vane 74 in a counter-clockwise direction will permit weight 75 to rotate vane 74 for reducing the rate of bleed through tube 71.

Figure 5 represents the pneumatic relay or pilot valve device previously referred to which forms the upper part of the control instrument. In practice, the casing enclosing the relay is formed integrally with the body of the control instrument but it is to be understood that the relay may be constructed separately and operatively associated with the other parts of the instrument so as to function in the same manner as when it is formed as an integral part thereof.

The relay comprises generally the casing indicated at 100, the lower part of which may be integrally connected to the body 1 of the instrument as shown on Figure 5. The casing 100 is made up of sections 101, 102 and 103, the sections being spaced by diaphragms of the same general circular conformation as the casing sections, all of the elements being rigidly secured together by screws 73. Communicating with the inner end of the opening 106 to which channel 5a connects is a transverse conical opening 109 in which is screw threaded a plug 110 which forms a needle valve which can be adjusted by means of a screw driver. Plug 110 is provided with a small longitudinal air passage as shown. The upper part of the opening 109 is sealed by a screw plug 112 leaving a space between the plug 112 and the needle valve member 110. The needle valve forms a restriction to the supply of air under pressure through pipe 5c and channel 5a, and the air which passes the restriction formed by the needle valve passes through a channel 115. The channel 115 communicates with a similar aligned channel in the sections 102 and 103 and with registering orifices in the diaphragms 104 and 105 which space the sections. The channel 115 connects with a shorter channel 116 in the section 103 of the casing which communicates with the chamber 117 formed within the section 103 between the diaphragm 105 and the inner wall of the section 103. The tube 71 having the bleed port 78 communicates with the chamber 117 so that air is allowed to bleed from this chamber at a rate as determined by the position of the baffle plate 76 with respect to the bleed port.

Formed in the section 101 of the casing of the relay device is a screw threaded opening for receiving a plug 120. Also formed within the section 101 at the inner end of the plug 120 is an opening 121 which communicates by a passage 122 with the opening 106. Centrally arranged within the plug 120 is an opening 125 arranged to receive the stem 126 of a valve member 127, the stem 126 forming a plunger in the opening 125. Around the walls of the opening 125 is formed another opening 128 of annular cross-section which receives a coil spring 129, one end of which engages the inner surface of the plug 120 and the other end of which engages the valve member 127. The seat for the valve member 127 is formed by an opening 131 in an internal wall portion 132 of the section 101. The coil spring 129 biases the valve 127 against its seat, as shown.

Within the casing 100 of the pneumatic relay device, a chamber is also formed within the section 102 between the diaphragms 104 and 105. Interposed between the two diaphragms within

phragms 104 and 105 will be moved to the right. The valve seat formed by tubular element 140 will thus be moved away from the valve member 127 allowing pressure to be exhausted from chamber 139 through the tubular element 140 into the chamber between the diaphragms and to the atmosphere through port 143. As soon as the forces exerted within chambers 139 and 117 again balance, the tubular element 140 will again seat against the valve member 127 and the system will again be in equilibrium. When the pressure in chamber 139 is reduced by reason of air being exhausted therefrom through the tubular element 140, this reduction in pressure will, of course, be communicated to the valves 89 and 90 and will cause the springs within the bellows operating devices to move the valve in opening direction. From the above, it is readily seen that the valves 89 and 90 are positioned in response to the temperature surrounding the thermostatic element 21 and admit steam at a rate so as to maintain a constant room temperature.

In the evening when it is desired to reset the control instruments of the system so as to maintain a lower temperature during the night, the three-way valve 88 may be reset from the basement or wherever the air compressing apparatus may be located so as to put pipe 87 in communication with the pipe 5. A constant pressure of 30 lbs. per sq. inch will now be communicated to the restrictor 110a, to the chamber 121, and through the branch connection 5b to the bellows 24. As has previously been explained in connection with Figures 1 to 4, this increased pressure within the bellows 24 will reset the control instrument by repositioning the thermostatic element 21. By reason of its new mounting position, the thermostatic element 21 will operate to maintain a substantially lower temperature at night. This temperature which is to be maintained at night can be adjusted by means of the knurled knob 36 which has already been described in connection with Figures 1 to 4. Obviously, the amount which the lever 16 carrying the thermostatic element is moved to the right, as seen on Figures 1 to 4, is determined by the position of the screw member 35 which forms a stop for the lever 16. The knurled knob 36 is located within the casing of the instrument and adjustment thereof is not intended to be made without removing the casing from the instrument.

With a pressure of 30 lbs. per sq. inch in the header 5c, it is readily seen that the pressure beyond the restricting device 110a may at times exceed the original normal value of 15 lbs. per sq. inch at which the supply pressure is maintained during the daytime. For example, when the bleed port is completely closed, a pressure of 30 lbs. per sq. inch will be applied to the diaphragm 105. Inasmuch as the relay mechanism tends to maintain the same pressure within chamber 139 and the valve motors as occurs within chamber 117, the relay device would tend at this time to apply a pressure of 30 lbs. per sq. inch to the valve motors. This is undesirable as this additional pressure may injure the valve motors. In order to prevent this result from occurring, the section 102 of the relay device 100 as seen in Figure 6 is provided with an internal shoulder 141a which corresponds to the shoulder 141 of Figure 5. This shoulder serves as a stop for limiting movement of the diaphragm 105 to

the left. Due to the spring action of the spring member 137, this member must be compressed in order to increase the force applied to the diaphragm 104 by the diaphragm 105. Upon an increase in pressure applied to the diaphragm 105 this diaphragm will be forced to the left thereby acting through the spring 137 to force the diaphragm 104 to the left which will shift the air valve member 127 from its seat for permitting air under pressure to enter the chamber 139. As described above air will be permitted to enter this chamber until the pressure therein rises sufficiently to force the diaphragm 104 back to its neutral position at which both the air valve and vent valve are closed. While the diaphragm 104 will normally be in its neutral position, this increase in pressure will have caused the diaphragm 105 to assume a position further to the left, this leftward shift of the diaphragm 105 being permitted by the resiliency of the spring member 137. Thus as the pressure in chamber 117 is increased the diaphragm 105 will assume positions more and more to the left, due to the fact that the spring member 137 must be compressed sufficiently to balance the pressure applied to diaphragm 105. The spring member 137 and the position of the shoulder 141a are correlated so that when a pressure of 15 lbs. per sq. inch is applied to the diaphragm 105, the diaphragm will be forced to the left against the action of spring member 137 to just engage the shoulder 141a. At this time the spring member 137 must necessarily have been compressed sufficiently to balance the force applied to diaphragm 105 by the air pressure. Inasmuch as this spring member is urging the diaphragm 104 to the left it is necessary that the pressure in chamber 139 be sufficient to maintain the diaphragm 104 in its neutral position and simultaneously provide the necessary reaction for the spring member 137. Thus with the diaphragms 104 and 105 of equal area the pressure maintained in chamber 139 will equal that in chamber 117 or in other words, at this time the pressure in chamber 139 will be 15 lbs. per sq. inch. Due to the fact that the diaphragm 105 is engaging its stop, further increase in pressure on this diaphragm cannot cause it to move any further to the left. The spring member 137 will therefore not be further compressed and consequently the pressure on diaphragm 104 will not have to exceed 15 lbs. per sq. inch in order to maintain this diaphragm in its neutral position at which both the air supply and vent valves are closed.

As has previously been explained in connection with Figures 1 to 4, after the control instrument has been reset as above described to maintain a lower temperature at night, the instrument may be returned to its original daytime setting by an occupant of the room as desired. This is accomplished by a counter-clockwise movement of the operating lever 47 so as to collapse the bellows 24 and reposition the thermostatic element 21 to its original position. The shaft 48 carrying the operating lever 47 extends through the side wall of the casing enclosing the instrument so that this adjustment of the instrument can be conveniently made by anyone whenever desired. If for any reason, the operating lever 46 should be left in the position shown in Figure 4, that is, the instrument having been returned to its daytime setting after having been reset for night temperature, when the pressure within the pneumatic system is

again reduced from 30 lbs. to 15 lbs. per sq. inch, the operating lever will automatically return to its normal position as seen in Figures 2 and 3.

Figure 7 represents a pneumatic relay device similar to that of Figure 5 but slightly modified in form. Corresponding elements of Figure 7 are correspondingly numbered to those of Figure 5. The diaphragms 204 and 205 of Figure 7 have annular corrugations as distinguished from the diaphragms of Figure 5. Also a third diaphragm member 241 is employed, the peripheral edges of which are retained between the diaphragm 204 and section 202 of the relay device. The internal portion of the diaphragm 241 is offset from its peripheral portions so that it forms a stop for the diaphragm 205 operable in the same manner as the stop formed by the flange 141 of Figure 5. Diaphragm 205 carries a central spring retaining element 244 and between this element and the tubular element 240 is a coil spring 236 which has the same function as the spider type spring 136 of Figure 5. The operation of the device of Figure 7 is the same as that of Figure 5 and has previously been explained in connection with Figures 5 and 6.

From the foregoing, it should be apparent that my improved control instrument avoids certain inherent disadvantages in similar devices heretofore known in that its design automatically prevents undesirable large pressures from being communicated to pneumatically driven valves or damper motors or the like. As is well known in the art, these devices are relatively sensitive and must be controlled with considerable precision in order to maintain desired temperatures in buildings being heated or cooled. If pressure beyond that necessary to cause complete closure of these devices is allowed to be communicated to them, the operating mechanism may be given a permanent set or other damaging results to the device may occur. That portion of the structure of the control instrument which provides for returning it to a daytime setting as desired after the control instruments of the system have been reset to a night temperature makes for economical operation of the heating system or the like as a whole inasmuch as an individual room may be maintained at a desired daytime temperature as long as desired after other rooms of a building have become unoccupied without supplying heat to the entire building at a normal daytime rate.

As there are many modifications, variations and changes in the form and application of the invention which will occur to those skilled in the art, it is to be limited only as determined by the appended claims.

I claim as my invention:

1. In a controlling instrument, in combination, a condition responsive element, means actuated by said element, said element being pivotally mounted so that it may move as a lever, resilient means including a pressure responsive member for positioning said element, means comprising a lever pivoted so as to engage said pressure responsive member, and operating means for said lever comprising a torsionally biased rock shaft having a flat surface for frictionally engaging said lever, said pressure responsive device acting on said lever to provide a sufficient degree of frictional engagement between the rock shaft and lever whereby the rock shaft is prevented from being rocked by the torsional bias.

2. In a control instrument, in combination, a condition responsive element, means actuated by

said element, resilient means including a pressure responsive device for positioning said element, a bell-crank lever pivoted so that one arm engages said pressure responsive device, a rock shaft having a flat side adjacent the other arm of said bell-crank lever, said pressure responsive device being operable to move said other arm substantially against said flat side, means comprising a dog for rotating said rock shaft and a torsion spring for resisting rotation of the rock shaft, rotation of the rock shaft being operable to move said bell-crank lever whereby said pressure responsive device is compressed, said rock shaft having a second relatively small flat surface for frictionally engaging said other arm of the bell-crank lever and retaining the rockshaft in rocked position against the torsion exerted by the torsion spring.

3. In a pneumatic temperature control system, in combination, a branch line connected to a pneumatic motor, a supply line for supplying air to said branch line, valve means for controlling the pressure in said branch line, diaphragm means responsive to the pressure in said branch line for controlling said valve means in a manner to vary the branch line pressure in accordance with a force applied to said diaphragm means, a second diaphragm means, a resilient connection between said first diaphragm means and said second diaphragm means for normally causing said second diaphragm means to apply force to said first diaphragm means in accordance with pressure applied to said second diaphragm means, pilot valve means for controlling the pressure applied to said second diaphragm means from said supply line, a condition responsive element for actuating said pilot valve means, movable mounting means for said condition responsive element, first adjustable stop means for limiting movement of said mounting means in one direction, biasing means for urging said mounting means toward said first stop means, a second stop means for limiting movement of the mounting means in the opposite direction, a pressure motor connected to said supply line for urging said mounting means toward said second stop means, a controller for raising and lowering the pressure in said supply line for causing said mounting means to be urged against either said first or second stop means, and stop means associated with said second diaphragm means for limiting the force applied by said second diaphragm means to said first diaphragm means through said resilient connection for thereby preventing the branch line pressure from being raised above a predetermined value even though the supply line pressure is raised above such value by said controller.

4. In a pneumatic temperature control system, in combination, a branch line connected to a pneumatic motor, a supply line for supplying air to said branch line, valve means for controlling the pressure in said branch line, diaphragm means responsive to the pressure in said branch line for controlling said valve means in a manner to vary the branch line pressure in accordance with a force applied to said diaphragm means, a second diaphragm means, condition responsive means for varying the pressure applied to said second diaphragm means, a resilient connection between said first and second diaphragm means, stop means for limiting movement of said second diaphragm means, for thereby limiting the force applied to said first

diaphragm means by said second diaphragm means through said resilient connection, adjusting means for varying the standard of the condition maintained by said condition responsive means, a pressure motor responsive to supply line pressure for actuating said adjusting means, and means for varying the pressure in said supply line for actuating said pressure motor.

5. In a pneumatic control system, in combination, a source of fluid under pressure, means for selectively changing the pressure of said source between predetermined higher and lower values, a control device adapted to be positioned by variations in the pressure of fluid applied thereto, valve means for controlling the pressure transmitted from said source to said control device, a first diaphragm means responsive to the pressure in said control device for controlling said valve means, a second diaphragm means, condition responsive means for varying the pressure applied to said second diaphragm means between a minimum pressure and the pressure at said source, means for transmitting the force applied to said second diaphragm means to said first diaphragm means, means for limiting the force transmitted from said second diaphragm means to said first diaphragm means to a predetermined value, adjusting means for varying the standard of the condition maintained by said condition responsive means, and a pressure motor responsive to the pressure of said source for actuating said adjusting means.

6. In a pneumatic control system, in combination, a source of fluid under pressure, means for selectively changing the pressure of said source between a lower value and a higher value, a control device adapted to be positioned by variations in the pressure of fluid applied thereto, valve means adapted to admit selectively pressure from said source to said control device or exhaust said control device, a first diaphragm, a pilot valve adapted to control the pressure transmitted from said source to said first diaphragm, a second diaphragm subject to the pressure in said control device, a resilient connection between said first and second diaphragms, means to prevent movement of said first diaphragm beyond a position corresponding to the lower value of the pressure of the source, a condition responsive device for positioning said pilot valve, and means responsive to the pressure of said source for selecting the value of the condition at which said condition responsive device actuates said pilot valve.

7. In a pneumatic temperature control system, in combination, a branch line connected to a pneumatic motor, a supply line for supplying air to said branch line, valve means for controlling the pressure in said branch line, diaphragm means responsive to the pressure in said branch line for controlling said valve means in a manner to vary the branch line pressure in accordance with a force applied to said diaphragm means, a second diaphragm means, a resilient connection between said first diaphragm means and said second diaphragm means for normally causing said second diaphragm means to apply force to said first diaphragm means in accordance with pressure applied to said second diaphragm means, pilot valve means for controlling the pressure applied to said second diaphragm means from said supply line, a condition responsive element for actuating said pilot valve means, movable mounting means for said condition responsive element, first adjustable stop

means for limiting movement of said mounting means in one direction, a second stop means for limiting movement of the mounting means in the opposite direction, a pressure motor connected to said supply line for moving said mounting means between said stop means, a controller for raising and lowering the pressure in said supply line for causing said mounting means to be urged against either said first or second stop means, and stop means associated with said second diaphragm means for limiting the force applied by said second diaphragm means to said first diaphragm means through said resilient connection for thereby preventing the branch line pressure from being raised above a predetermined value even though the supply line pressure is raised above such value by said controller.

8. In a fluid pressure relay, in combination, a first chamber adapted to be subjected to a variable pressure, a second chamber the pressure in which normally is controlled in accordance with the pressure in said first chamber, a first diaphragm subjected on one side to the pressure within said first chamber, a second diaphragm subjected on one side to the pressure within said second chamber, a mechanical connection between said diaphragms including a resilient portion, pressure inlet and exhaust valves for controlling the pressure in said second chamber and adapted to be opened selectively by said second diaphragm, and stop means for limiting movement of said first diaphragm.

9. In a fluid pressure relay, in combination, a first chamber adapted to be subjected to a variable pressure, a second chamber the pressure in which normally is controlled in accordance with the pressure in said first chamber, a first diaphragm subjected on one side to the pressure within said first chamber and on the opposite side to atmospheric pressure, a second diaphragm subjected on one side to the pressure within said second chamber and on the opposite side to atmospheric pressure, pressure inlet and exhaust valves for controlling the pressure in said second chamber and adapted to be opened selectively by said second diaphragm, connecting means between said first and second diaphragms including a resilient portion adapted on a rise in pressure within said first chamber to open said inlet valve, and stop means adapted to prevent movement of said first diaphragm beyond a position corresponding to a predetermined relatively high pressure thereby limiting the pressure which will be admitted to said second chamber.

10. In a pneumatic control system, in combination, a source of fluid under pressure, means for selectively changing the pressure of said source between predetermined higher and lower values, a control device adapted to be moved to a first limiting position at a predetermined relatively low pressure of fluid applied thereto and to a second limiting position at a relatively higher pressure substantially equal to the lower pressure available from said source of pressure, valve means for controlling the pressure transmitted from said source to said control device, a first diaphragm means responsive to the pressure in said control device for controlling said valve means, a second diaphragm means, condition responsive means for varying the pressure applied to said second diaphragm means between a minimum pressure and the pressure at said source, means for transmitting the force applied

to said second diaphragm means to said first diaphragm means, means for limiting the force transmitted from said second diaphragm means to said first diaphragm means to a predetermined value whereby the pressure admitted to said control device is limited substantially to the lower pressure available from said source, ad-

justing means for varying the standard of the condition maintained by said condition responsive means, and a pressure motor responsive to the pressure of said source for actuating said adjusting means.

PAUL F. SHIVERS.
